UNITED STATES PATENT OFFICE.

CHARLES ALLEN, OF EL PASO, TEXAS.

SLIME-PULP THICKENER.

1,360,703.

Specification of Letters Patent. Patented Nov. 30, 1920.

Original application filed June 9, 1917, Serial No. 173,785. Divided and this application filed October 10, 1918. Serial No. 257,623.

To all whom it may concern:

Be it known that I, CHARLES ALLEN, a citizen of the United States, residing at El Paso, in the county of El Paso and State of Texas, have invented new and useful Improvements in Slime-Pulp Thickeners, of which the following is a specification.

This invention relates to a device for thickening slime or pulp, and particularly 10 pertains to a structure similar to that disclosed in my co-pending application entitled, "Slime pulp thickener," Serial Number 173,785, filed June 9, 1917, and of which the present application is a division.

15 Thickening, which is a partial dewatering of finely divided solids in suspension, is almost universally used in the treatment of ores by wet milling processes, and in its every application it is of prime importance that the degree of thickening be uniform; that is, that the discharge of the thickened slime be always of the same density. Thick- 20 eners heretofore used depend upon the volume of pulp fed to the cone or tank for regulation of the size of the discharge orifice. The results are very unsatisfactory, inasmuch as the proportion of liquids to solids in the material discharged varies with the volume of slime pulp fed to the thickener.

25 In the present invention, the volume of slime pulp in the thickener in no manner alters the proportion of liquids to solids in the products discharged, within the limits of the capacity of the machine. The degree of thickening is controlled, and for whatever degree of thickening the device is adjusted, that degree of thickening is automatically maintained.

In slime pulp, the finely divided solids 30 move freely without appreciably affecting the fluidity by friction among themselves. Such a pulp has the properties of a liquid so long as the solids are kept in suspension. When the pulp is composed of water and 35 solid particles of greater specific gravity than water, the specific gravity of the pulp increases with all increases in the quantity of solids in suspension in the pulp. This pulp may therefore be considered as a liquid of greater density than water.

40 In my invention I employ what may be termed two compartments having in one compartment a liquid, and in the other a mixture of liquid and solids or pulp. These 45 compartments are so arranged that the vari-

ations in the density of the pulp, due to the presence of more or less solids in suspension, act to raise and lower the column of liquid, which column of liquid carries a float operatively connected to a valve at the bottom of 50 the tank controlling the discharge orifice. When the pulp attains a certain density the valve is automatically opened to permit the discharge of the thickened pulp through the bottom orifice, and when the density of the 55 pulp falls below a critical point, the valve is automatically operated to close the orifice. Hence the degree of thickening of the pulp discharged through the automatically controlled orifice is practically the same under 60 all conditions or variations in the volume of slime pulp fed into the tank. The volume of thickened slime discharged through the orifice may vary considerably, but the density of the thickened slime discharged 65 remains practically constant. This is the reverse of the thickeners ordinarily used in which the volume of thickened slime discharge remains constant while the density of the discharge varies with the quantity fed 70 into the thickener.

The invention is illustrated by way of example in the accompanying drawing in which the figure discloses the complete apparatus, as seen in central, vertical section.

Referring more particularly to the drawing, the apparatus is shown as comprising a tank 10 in the shape of an inverted cone having a discharge orifice 11 at its bottom for carrying off the thickened product. A 75 launder 12 is arranged around the top of the tank for carrying off clear liquid which overflows the rim of the tank. A conduit 13 is provided to supply slime pulp to the center of the tank. The outlet 11 of the tank is indirectly affected by a float 14 having variable buoyancy due to the application of adjustable weights 15. This float is provided with operable connections 16 which extend 80 downwardly and engage the mechanism of a valve 17 controlling the discharge orifice 11. In the present instance the float is circular, being positioned within an annular chamber 18 which has outer and inner concentrically spaced walls forming the float chamber, at 85 the same time separating it from a central, vertical opening through which the pulp passes to the tank from the conduit 13. The float chamber 18 is of sufficient height to extend to a level considerably above that of the 90

- rim of the tank and further extends downwardly to a level below the rim of the tank. This chamber is supplied with clear water through an inlet supply pipe 22.
- 5 The float chamber is provided with a series of connecting elements 20 which extend downwardly from the lower tapered wall thereof. The lower ends are in communication with a rubber or other flexible bag 23.
- 10 This bag is filled with clear water adapted to pass into the float chamber 18 through the openings 20. The fluid in the bag does not come in contact with the material in the tank and hence it is impossible for the 15 clear water to become contaminated. Due to the fact that the bag is of flexible material and that there is a difference in density of the contents of the tank around the bag and the contents of the bag and the super-
- 20 imposed column in chamber 18, it is possible for the float 14 to be actuated and thus to regulate the discharge valve at the bottom of the tank.

It will be readily understood that the 25 slime which thickens within the tank will at the same time increase in weight and will therefore increase the external pressure on the bag to contract the same and raise the level of the water in the float chamber. 30 The contraction will take place until hydrostatic balance is produced between the liquid within the bag and the surrounding liquid within the tank. It will be evident that the 35 static balance would be the same as though there was no membrane interposed between them. In this instance, however, the clear water will be protected. It is also obvious that any other medium sensitive to the dif- 40 ferent pressures caused by the increase or decrease in the density of the slime pulp, such as a free working sleeve or a mercury seal, could be used instead of the bag with equally desirable results, the working sleeve 45 lifting the pulp in the float chamber bodily while the action of the mercury seal would be similar to the action of the bag.

By analysis it will be seen that the float chamber 18 and the bag 23 constitute one of 50 the compartments before referred to and the tank and its pulp forms the other. These two compartments are so arranged as to stand in hydrostatic balance in relation to each other as permitted by the flexibility of 55 the bag. The variation in the density of the pulp outside the bag 23 will act to vary the height of the column of water within the chamber and will thereby directly produce a raising or lowering of the float and through 60 this action open or close the discharge orifice.

In the present instance, the actuating force is the difference in the density of the contents of the tank and the chamber 18, which, to maintain a hydrostatic balance,

raises the surface of the liquid in the compartment containing the liquid of lesser density above the level of the surface in the compartment containing the material of greater density. This difference of level is directly proportionate to the difference in the densities of the liquid. If it is assumed that the tank is filled with water as well as the bag 23 and the column 18, the vertical length of the columns would be the same; that is, the level of their surfaces would be 75 the same. If, without altering the length of the column, the density of the contents of one liquid column of the apparatus, is increased; say, one-tenth. Then to maintain a hydrostatic balance, the length of the opposing column must be increased one-tenth. Applying this to the device here shown, the proportion of the tank 10 above the lower end of the bag 23 will represent one liquid column and the chamber 18, and the bag 80 with the connecting elements 22, the other column.

The chamber 18 and the bag contain clear water and therefore represent the column of less density while the thickened slime in the 90 tank represents liquid of greater density. Therefore, to maintain a hydrostatic balance between the two columns, the water level in the float chamber will, of necessity, be higher than the level of the thickened slime in the tank and directly in proportion to the excess in density of the contents of the tank over that of the contents of the float chamber and its associated parts.

Assuming this difference in the density of 100 the liquids in the two columns to be 0.25 and the length of the both columns when occupied by a liquid of the same density, to be 25 inches. Then the difference in the length of the two columns would be 6.25 inches. To 105 prepare the device for operation, the bag 23 and the chamber 18 are filled with clear water to a predetermined height in the chamber. Slime pulp is then admitted to the tank through the conduit 13 and as the liquid contents of the tank thereafter overflows the 110 rim thereof, the thickening process will take place.

It will thus be seen that an apparatus is 115 here provided which will automatically operate to maintain the slime at a uniform density, said operation being dependent upon the hydrostatic balance of the two liquids varying in density. It is to be understood that wherever the word "water" or "liquid" 120 has been used in the foregoing specification, that these terms include any other liquid or solution employed in practical milling operations.

Having thus described my invention, what 125 I claim and desire to secure by Letters Patent is—

1. In a thickener for slime pulp and the

- like, a settling tank having a controllable orifice for the discharge of the heavier and more quickly settling particles, and an overflow rim for the lighter and more slowly settling particles, a fluid column of fixed density in operative relation to the material to be thickened and affected by variations in the density of said material to cause a change in the elevation of the fluid column, means to prevent the material in the tank from entering the fluid column, and means actuated by the rise and fall of the fluid column to control the size of the discharge orifice in the tank.
- 15 2. A thickener for slime pulp comprising a tank, and a discharge orifice for the discharge of the settled material contained therein, a fluid compartment having flexible walls disposed within said tank and adapted to register the variations of pressure caused by the change in the density of settled material surrounding the compartment by the raising and the lowering of the fluid contained therein, a float in said fluid compartment, and connecting means between said float and discharge orifice whereby settled material of a certain density is automatically discharged.
- 30 3. A thickener for slime pulp comprising a tank having a discharge orifice for the discharge of settled material, a bag made from flexible material disposed within said tank, a float chamber disposed above said bag and having communication therewith, said bag being adapted to register the change in pressure due to the change in density of the surrounding material by raising and lowering the level of the fluid within said float chamber, a float within said chamber and operating connections between the float and the dis-

charge orifice whereby settled material of a certain density is discharged automatically.

4. A thickener for slime pulp comprising a tank having a discharge orifice adapted for the discharge of settled material therein, a fluid compartment having flexible walls disposed within said tank, a float chamber above said compartment and in communication therewith, the fluid having a predetermined height in said float chamber, adapted to give a hydrostatic balance between the column of fluid in said compartment and float chamber and the liquid in the tank, a float in said chamber and connecting means between said float and controllable orifice whereby settled material of a predetermined density is discharged.

5. A thickener for slime pulp comprising a tank having a discharge orifice for thickening material in the bottom thereof, a fluid compartment having flexible walls disposed within said tank, a float chamber disposed above said compartment and in communication therewith, a float in said chamber whereby the change in pressure, due to the variation in the density of the pulp surrounding said compartment, is registered, adjustable means for regulating the buoyancy of the float, and means for connecting said float with a discharge orifice whereby the discharge of liquid of a predetermined density is had.

In testimony whereof I have hereunto set my hand in the presence of two subscribing witnesses.

CHARLES ALLEN.
